UNITED STATES PATENT OFFICE

EVERETT WORTHINGTON, OF CHICAGO, ILLINOIS, ASSIGNOR TO THE RICHARDSON COMPANY, OF LOCKLAND, OHIO, A CORPORATION OF OHIO

DESIGN FOR A COMPARTMENT PLATE OR SIMILAR ARTICLE

Application filed November 12, 1931. Serial No. 41,700. Term of patent 7 years.

To all whom it may concern:

Be it known that I, EVERETT WORTHINGTON, a citizen of the United States, and a resident of Chicago, in the county of Cook and State of Illinois, have invented a new, original, and ornamental Design for a Compartment Plate or Similar Article, of which the following is a specification, reference being had to the accompanying drawing, forming part thereof.

In the drawing:

Figure 1 is a perspective view of a compartment plate or similar article, showing my new design.

Figure 2 is a plan view of the same.

I claim:

The ornamental design for a compartment plate or similar article, as shown.

EVERETT WORTHINGTON.
